WAVE TRANSMITTING AND AMPLIFYING

Original Filed Dec. 30, 1921 2 Sheets-Sheet 2

UNITED STATES PATENT OFFICE

RAYMOND A. HEISING, OF MILLBURN, NEW JERSEY, ASSIGNOR TO WESTERN ELECTRIC COMPANY, INCORPORATED, OF NEW YORK, N. Y., A CORPORATION OF NEW YORK

WAVE TRANSMITTING AND AMPLIFYING

Application filed December 30, 1921, Serial No. 525,906. Renewed November 6, 1928.

This invention relates to improvements in systems and methods of wave transmission and more particularly in radio transmitting systems. Certain features (however, are of 5 general application and may be employed, for example, in, receiving systems, wire transmission systems, repeaters, or other apparatus employing electron discharge devices. Other features, however, are not 10 limited in application to systems utilizing electron discharge devices but may be otherwise employed.

One object of the invention is to provide means for multiplex communication with a 15 single antenna and in carrying out this object, use is made of a multiply tuned antenna system, that is a system adapted to offer low impedance to impressed currents of different frequencies. Shunt paths to the antenna 20 are provided for giving the antenna system additional degrees of freedom and an impedance or excluding circuit is included in each path to prevent the passage therethrough of waves of other frequencies.

25 The invention also comprehends improvements in modulating systems and methods. Use is made of an oscillator to produce a modulated high frequency wave, and one or more amplifiers are arranged to repeat this 30 wave. With one condition of adjustment of the amplifiers, the wave will be amplified without material distortion. However, with another condition of adjustment the portions of the modulated wave of greatest amplitude 35 will be amplified to a greater extent than those portions of least amplitude thereby effecting a further modulation as explained hereinafter in greater detail. Certain broad aspects of this feature are defined in 40 the claims. Filters are provided for preventing the output circuits of the amplifiers from reacting on each other by power transferred through the antenna circuit.

A further object is to provide means in 5 radio transmitting systems for rendering the carrier frequency independent of the condition of the transmitting antenna and independent of the amplitude or wave form of the 10 modulating wave. In other words, rapid or slow variations, either in the condition of the

antenna or in the condition of the variable impedance device which controls the amplitude of the transmitted waves, do not change the transmitted frequency. This is accomplished by generating a wave of relatively 55 low power and of constant amplitude and frequency, and variably amplifying this wave in a repeating device. The "constant current method" of controlling the repeating device is preferred. The advantages of this method 60 are generally known and need no extended discussion. From a generic standpoint, however, the invention is not limited to this method of modulation and other methods may be employed.

65 The amplified waves are impressed on the transmitting antenna. In some instances, one or more additional repeating devices are connected between the first repeater or amplifier and the antenna. Since even the best 70 known high frequency amplifiers have some measure of distorting action, a still further refinement consists in placing a filter circuit between the last repeater and the antenna. This filter circuit is of importance in multiplex 75 operation, that is, in systems where a plurality of high frequency waves are impressed upon a single radiating structure. The filter is designed to permit the passage of a particular frequency from the amplifier to the antenna and to suppress other frequencies tending to pass from the antenna back to the amplifier. For a similar reason, modulating 80 systems of the kind described may be advantageously applied in multiplex systems, because the element of the transmitter which is adjacent the transmitting antenna is an amplifier which does not allow appreciable reaction from the antenna back upon the oscillator which generates the carrier frequency current. This is not to say that such modulating 85 systems are not useful in systems transmitting only a single message at a time upon one antenna, but merely to point out a special advantage of this arrangement in connection 90 with plural channel systems. The possible reaction between the various channels is thus considerably reduced. This feature is still more important in multiplex high power systems because a relatively slight modulating 95 100

effect in the power amplifier will result in a very appreciable amount of unprofitable and undesirably modulated energy.

Other and more specific objects of the invention will be apparent from a perusal of the appended claims.

The various features of the invention will be better understood by reference to the following description, taken in connection with the accompanying drawings, wherein Fig. 1 represents a multiplex radio system having three transmitting systems for transmitting three telephone conversations simultaneously by means of one antenna, a complete circuit diagram of one of the systems being shown, the second system being outlined by rectangular blocks, and the third being merely indicated; Figs. 1a and 1b show alternative arrangements of the auxiliary tuning system for the antenna which may be substituted for that portion to the right of the line X—X in Fig. 1; Fig. 2 is a complete system which may be substituted for any one of the three transmission systems of Fig. 1, and Fig. 3 is a simplified circuit arrangement adapted to transmit modulated waves of a single frequency as well as waves of two frequencies each modulated in accordance with the same signal.

In Fig. 1, the line L represents any circuit such as a telephone line, in which are produced low frequency signaling waves to be transmitted upon a high frequency carrier wave. The low frequency waves are impressed upon the input circuit of a three-electrode electric discharge device V which typifies any variable impedance system. The anode-cathode circuit of the system V is supplied from the source 1 through a choke coil 2 which is adapted to prevent the passage of current variations having frequencies such as exist in line L.

Assuming that the switch "s" is positioned upon the contact 3 there will be connected in parallel with the system V with respect to the source 1 and coil 2, an oscillation generating system O, a high frequency amplifying system HA and a second high frequency amplifying system HA'.

Each of the systems V, O, HA and HA' may consist of a single vacuum tube or equivalent device or any suitable number of vacuum tubes or equivalent functioning devices arranged in parallel. The system V may be of any kind which efficiently varies the space current of the remaining tubes of the system.

The oscillating system O, as illustrated, is of a well-known type and generates high frequency oscillations in a tuned circuit comprising capacity 4 and inductance 5.

Space current is supplied to the system O through a radio frequency choke coil 6 which prevents high frequency variations from passing therethrough and being short circuited through the coil 2 and source 1 or either of them.

Resistance 7 serves to reduce the direct potential impressed upon the space current path of the system O while the capacity 8 allows speech frequency variations to pass readily.

The function of resistance 7 and capacity 8 is to cause the oscillations generated by the oscillator to be more completely modulated. By proper adjustment of the resistance the modulated oscillations may be made to fall to zero amplitude during each speech cycle. A further function is to cause a smaller direct current voltage to be applied to the plate circuit of the tube of the oscillator O than is applied to the tubes of the amplifiers HA and HA'.

Since the space current of the oscillator will be varied in accordance with low frequency variations of impedance in the system V, the waves generated by system O will be modulated in accordance with these low frequency waves.

The modulated waves produced are impressed upon the input circuit of the high frequency amplifying system HA, of which the output circuit is connected to the input circuit of the second amplifying system HA' for further amplification.

Assuming that switch "s" is positioned on contact 3, the space current of the system HA will be varied in a similar manner as that of the system O. The amplification ratio of the system HA will, as a result of this, tend to be moderately greater at those instants when the waves supplied to its input circuit are of large amplitude than at those instants when the waves supplied to its input circuit are of small amplitude. A variable amplification of the applied high frequency will, therefore, result, tending to produce a greater disparity in the amplitude of the waves in the output circuit of the system HA than exists in the waves supplied to the input circuit. The space current of the system HA' will undergo a corresponding variation and the effect of this system upon the waves supplied to its input circuit will be similar to that of the preceding amplifier. By moving the switch "s" to the contact 3', the amplifying system HA will not have its space current supplied through the coil 2 and hence it will tend to act as an ordinary amplifier. The coil 2 constitutes a high inductive impedance for waves of signaling, i. e. speech frequencies. Source 1 and coil 2 together form a highly inductive source.

Still other means are provided whereby the systems HA and HA' may be made to function as substantially distortionless or non-modulating amplifiers even though their space current is supplied through the coil 2. This is accomplished by providing in the input circuit of each of these systems, a leak 1

path consisting of a variable resistance 9 in shunt to a capacity 10.

5 The negative charge upon the grids 11 will increase when the amplitude of the waves supplied to the input circuit increases and decrease when this amplitude decreases, since this charge is at any instant due to the rate of supply of electrons from the filament combined with the rate of leakage through the resistance 9.

10 When waves of relatively larger amplitude are applied to the input circuit the supply of electrons to the grid is more rapid, hence when the amplitude of the supplied wave increases, the successive waves will cause a large leakage current to flow to the grids 11 as compared to the leakage current flowing when the amplitude is small. Since the amplification ratio of a discharge repeater of 15 this type tends to decrease as the negative charge upon the grid increases, it will be seen that this compensates for the variation in the amplifying power caused by low frequency variations in the anode-cathode potential supplied to the tube. The extent of this compensation may be varied through a wide range by variations in the capacity 10 and the resistance 9. It will also depend upon the particular design of the vacuum tube being used.

20 5 In some instances, it may be desirable to so adjust the systems HA and HA' that each will effect modulation of the waves thereby. In other instances, however, it may be desirable to so adjust the systems that the minimum of such modulation is effected. Even though no modulation is taking place in both of these systems or either of them, there are certain advantages connected with the supplying of their space current through 25 the choke coil 2. An important one of these advantages is that the total energy consumption in the amplifying systems with a given high frequency energy output is reduced. The importance of the energy saving function 5 of a system of this kind is considerable and this feature is emphasized.

At instants, when the amplifying tubes are amplifying high frequency waves of large amplitude, they must have a large average 0 value of space current and when the are amplifying high frequency waves of small amplitude, a small average value of space current is sufficient. This is precisely what occurs. During the portions of the cycle of the 5 modulating frequency, when high frequency waves of large amplitude are produced, the average value of the space current is proportionally large. When the high frequency waves are of small amplitude the average value of the space current is small.

Furthermore, when the space current has the largest average value, the average impedance of the tube is the smallest and when the space current has the smallest average value, the impedance of the tube is, on the average,

the greatest. Efficient utilization of the energy supplied to the space current path of the tube system results. In this discussion of efficiency the consumption of energy in heating the filaments of the tubes is not considered. It is regarded as a constant quantity whose value in any particular case depends upon the maximum electron emission necessary to produce the greatest necessary instantaneous value of current flow through the tube.

The output circuit of the system HA' is coupled to the antenna system "a" by inductively related coils 12 and 13. Coil 12 is located in a path including condenser 14 and 70 inductance 15 which is tuned to the mean frequency generated by the oscillating system O. Shunt paths 16 and 17 are tuned by means of inductance and capacity to offer low impedance to waves of the frequencies produced by the oscillating system O of transmitters T1 and T2 respectively. The energy impressed upon the coil 12 from the systems T1 and T2 is thus short-circuited through the paths 16 and 17 and is not impressed to a material extent upon the space current path of the amplifier HA'. In this manner, intermodulation of the outgoing waves is prevented. The systems T1 and T2 may be identical with transmitter T except for the modification necessary to produce other frequencies, or they may differ from the transmitter T. One of these systems may, for example, be similar to that illustrated in Fig. 2, and the other similar to that in Fig. 3.

100 It is desirable that the antenna system "a" be given several degrees of freedom corresponding to the frequencies of the several carrier waves impressed thereon. This is conveniently accomplished in one manner by tuning the antenna to the shortest wave length to be radiated which we may assume will be that of transmitter T. A variable capacity 18 in shunt to the aerial-ground capacity of the antenna serves to tune to the next longer wave length which we may assume to be that of system T'. A loop-resonant circuit containing inductance 19 and capacity 20 is included in series with capacity 18 and is tuned to be resonant at the shortest 110 wave length, thereby offering a high impedance to the current of these waves.

The tuning for the next longer wave length is accomplished by adding a capacity 21 in shunt to the capacity 18 and providing an additional loop resonant circuit consisting of inductance 22 and capacity 23 for preventing the energy of the waves of the intermediate frequency from passing therethrough. In tuning, of course, the reactance of the loop resonant circuits for the waves to which they are not attuned will be allowed for in adjusting the capacities 18 and 21.

120 If desired, however, the antenna may be tuned to the longest wave length, in which 130

case, the arrangement used in Fig. 1a may be used. In this instance, tuning to the shorter wave length is accomplished by placing variable inductances 24 and 25 in shunt to the aerial-ground capacity of the antenna. By varying these inductances the desired tuning may be accomplished, the circuits 19, 20 and 22, 23 functioning as in Fig. 1.

Since, however, it is difficult to produce variable inductances of low resistance, it may be desirable to substitute for the inductances 24 and 25, combinations of elements (Fig. 1b) such as fixed inductances 26 and 28 in series with variable capacities 27 and 29 respectively. Each of these combinations is so designed that it will always present the required inductive reactance which may be varied by changing the capacity of the respective condensers.

It will be observed that the wave energy is most efficiently utilized at the frequency to which the antenna is tuned and less efficiently utilized as the frequency departs therefrom. For this reason, where equality of radiation is desired for given amounts of energy impressed upon the antenna, it is advisable to tune the antenna to the longest wave length and add auxiliary elements when tuning for the shorter wave lengths. This is because the radiation resistance of an ordinary antenna is greater for shorter waves and less for longer waves. By less efficiently utilizing the energy of the shorter waves, the radiation for a given amount of power supplied tends to be equalized.

An alternating current source 30 is provided to heat the cathodes of the vacuum tubes. The current is supplied through a transformer 31 across the secondary of which the filaments of the tubes are arranged in parallel. It will be noted that the terminals of the filaments 32 and 33 which are connected to the grids are connected to opposite terminals of the alternating current source. Thus, when the terminal of the filament 32, which is connected to its associated grid, is made positive by the alternating current the terminal of the filament 33 which is attached to its associated grid, is made negative. The same condition is true as regards the terminals of the two filaments which are connected to their respective anodes, but this is less important as the effect produced in the grid circuit is much greater. It will be seen that the distorting effect produced in the amplifying system HA by the alternating current heating source will be, to a large extent, compensated for by an equal and opposite effect produced in the system HA'. With respect to the system V and the system O and other similar combinations of oscillator and variable impedance tubes, it makes little differences whether their filaments are oppositely or similarly connected to the heating current source.

In general, the disturbance introduced seems to be comparatively small in either case.

The above described arrangements for heating filaments of a vacuum tube system are described and claimed in applicant's U. S. Patent No. 1,537,941 issued May 19, 1925.

Fig. 2 in general corresponds to transmitter T in Fig. 1. In the following description emphasis will be put upon the features distinguishing the two systems rather than the features common thereto.

The speech or low frequency currents existing in the line L, before being impressed upon the variable impedance system V, are amplified by means of a low frequency amplifier LA. Obviously, if the waves in line 1 are of sufficient power the amplifier LA may be omitted and the line L connected directly to the input circuit of the system V as in Fig. 1.

The source 1 comprises a mechanical generator; hence a filter F is provided to reduce fluctuations in the current therefrom. It will be noted that this current is supplied through a speech frequency choke coil 2 to high frequency amplifying systems HA' and HA'' which are arranged in tandem with respect to each other, but in parallel with respect to the anode circuit of variable impedance system V. By this means the modulation is entirely effected in the high frequency amplifying systems.

The current to be modulated is supplied by an oscillation generating system O, receiving its space current directly from the source 1. The current generated by system O is amplified by the high frequency amplifying system HA and impressed upon the input circuit of the system HA', of which the output circuit is connected to the system HA''.

The output circuit of each of the high frequency amplifying systems preferably contains a circuit tuned by inductance and capacity to be resonant to the same frequency as that produced by the oscillator O.

The resistance 7 and capacity 8 which are in circuit with the plate supply of the system HA function in a manner similar to the correspondingly marked elements in Fig. 1. The resistance 9 and the condenser 10 in the input circuit of the system HA'' likewise function similarly to the elements correspondingly marked in Fig. 1.

By proper adjustment the system HA'' may be made to function entirely as an amplifier or as an amplifier and modulator combined. No choke coils corresponding to those marked 6 in Fig. 1 are connected in circuit with the high frequency amplifying systems. The condensers 37 are of low impedance to high frequency and render the choke coils unnecessary. If condenser 37 of system HA is large it also will shunt speech frequencies around oscillator O. A suitable

source 37' is provided to polarize the grids of those of the amplifiers which are not equipped with leak path resistances.

The high frequency amplifying system HA'' may be omitted from the arrangement shown in Fig. 2 if desired. In this case, the antenna will be directly connected to the output circuit of the amplifier HA''.

Another modification is to omit the amplifying device HA' of Fig. 1 and couple the radiating antenna directly to the output circuit of the amplifying device HA. Device HA would then do the modulating.

Furthermore, in Fig. 2, both of the amplifying systems HA and HA' may be omitted and the oscillator O coupled directly to the input circuit of the amplifying system HA''. The last-mentioned modification, however, results in a system very similar to that of Fig. 20 hereinafter described.

Referring again to Fig. 2, it will be seen that the current of carrier frequency generated by the oscillator O cannot be appreciably varied in amplitude by any variation in condition of the variable impedance modulating system V or by any changes in capacity, impedance or resistance of the radiating antenna system. Furthermore, the currents produced in the radiating system by other channels cannot react back through the amplifiers upon the oscillating system O.

In the system illustrated, wherein a plate current source 1 is in common with the amplifier LA and the oscillator O, a reaction from the plate circuit of the amplifier LA upon the oscillator O appears possible at first glance. This, however, does not occur for reasons about to be stated.

The filter F, in a practical application, 40 consists of inductances of about 1.1 henries each and a shunt capacity 60 of about 4 microfarads. The power tubes in the amplifying systems HA and HA' require a plate voltage approximately twice as great as is desirable 45 for the oscillator O. This necessitates that the resistance connected in series with the plate supply of the oscillator O be about equal to the internal impedance of the tube itself.

The tube of the generator O is small and 50 requires a plate voltage of, for example, 350 V. and the generator 1 produces a high potential of 750 V. The average internal impedance of such a tube as is used for the oscillator O is five or six thousand ohms. The series 55 resistance will necessarily have a similar value of about five or six thousand ohms.

Since the impedance at mean speech frequency of the four-microfarad condenser 60 is very low relative to the impedance of the oscillator O in series therewith, this condenser will act as a practical short-circuit for oscillator O upon the transformer primary in the plate circuit of the amplifying system LA for speech frequencies. For these reasons the 65 direct reaction from the amplifying system

LA upon the oscillator O is entirely negligible. If the generator 1 is replaced by a battery or other source 1 as illustrated in Fig. 1 having small impedance at speech frequencies then the reaction of the amplifying system LA upon the oscillator O is correspondingly negligible. 70

The oscillator O functions as a means for establishing a definite frequency of carrier current. This frequency is not changed by 75 any changes in the constants of the antenna system or the amplifying systems HA, HA' or HA'', since these cannot react back upon the oscillator except for such negligible changes of impedances as might occur in the input circuit of amplifier HA. 80

Since the modulation is accomplished principally in the amplifying system HA'' and not at all in the amplifier HA, the frequency of the oscillator O does not change as the modulating wave form or its amplitude changes. Likewise, the variable impedance system V cannot act directly upon the oscillator O even through the plate supply source 1 because the choke coil 2 is necessarily of high inductance 90 and has a very high impedance at speech frequencies. 95

The filament heating system of Fig. 2 is supplied from the alternating source 30 through the transformer 31. The secondary 95 of the transformer 31 may be regarded as a source of heating current. Mains 38 and 39 are connected across the terminals of this secondary. A neutral connection 40 is provided to which one terminal of each of the 100 filaments is connected.

Where a single vacuum tube, as, for example, LA is utilized for performing one function, this may be connected from the neutral 105 40 to one main 39 while this is balanced by the filament of another system, such as that of the system O connected between the neutral 40 and the main 38. Thus, for example, it will be seen that the filaments of the systems O and HA are oppositely connected 110 with respect to the neutral lead of the heating current supply system. 110

The effect produced in one of these systems tending to modulate current in accordance with the alternating heating current will be compensated for to a large extent by the opposing effect produced in the other of the systems. Where, however, a plurality of tubes in parallel are used for performing a certain function, as in the systems V, HA' 120 and HA'', part of the filaments may be connected across one side of the heating current system and the other part across the other side. In this case, the effect produced in one tube of system V for example, is 125 compensated for by the effect produced in the other tube of the system V, since, when one cathode is made positive with respect to its associated grid, the other cathode is made correspondingly negative. Suitable 130

filament rheostats 41, individual to each filament, are provided.

Ordinarily, no connection from the neutral conductor 40 to any intermediate point of the secondary of the transformer 31 is essential. If, however, the two halves of the systems are seriously unbalanced, such a connection as illustrated by the conductor 42 may be provided.

10 The filament heating systems of Figs. 1 and 2 are interchangeable. A direct current filament heating system may be substituted for the alternating current filament heating system by eliminating the source 30 and the 15 primary of the transformer 31, and substituting two substantially equal direct current batteries for each of the halves of the secondary winding of the transformer 31.

In Fig. 3, provision is made for amplifying in an amplifier 50, high frequency carrier waves from either or both of two oscillators O and O'. These oscillators are of the well-known three-electrode vacuum tube type as illustrated. Their frequencies 25 may be of any value suitable for radiation, for example, that of the oscillator O may be 550,000 cycles and that of the oscillator O' 450,000 cycles or 500,000 cycles.

The frequency of either may be adjusted 30 or changed by means of the variable condenser in the oscillatory frequency-determining circuit. The waves from either or both of these oscillators may be impressed upon the amplifier 50 by closing one or both 35 of the keys K and K' respectively. The waves impressed upon the input circuit 51 are caused to appear in the output circuit of the amplifier 50 with their amplitude varied in accordance with signaling waves, 40 that is, modulated in accordance with signaling waves in a microphone circuit 52.

The circuit 52 typifies any signaling circuit, for example, a telephone line. A three-electrode space discharge device 53 is connected in parallel with the amplifier 50 with 45 respect to the source of current 54 which supplies energy to the anode-cathode circuit of each of the devices 50 and 53. A choke coil 55 having high impedance at 50 speech frequencies maintains the sum of the currents flowing through the devices 50 and 53 constant.

A high frequency choke coil 56 prevents high frequency energy in the anode circuit 55 of the device 50 from being shunted through the device 53. A condenser 57 of low impedance to the frequencies produced by the oscillators O and O' is included in the plate circuit of the device 50 in order to prevent 60 short-circuiting of its anode-cathode path. The amplified waves are impressed upon the radiating antenna 58 or other equivalent transmitting conductor.

When one of the oscillators O and O' is 65 operating and the corresponding key K or

K' closed, the high frequency oscillations generated by that particular oscillator will be modulated in amplitude in accordance with speech waves in the circuit 52 and radiated by the antenna 58.

The frequency of the radiated waves may be changed by adjusting the frequency of the oscillator or by opening the key in its circuit and closing the key in the circuit of the other oscillator. For certain purposes, it 70 may be desirable to radiate two high frequency waves, for example, waves having frequencies of 550,000 and 500,000 cycles respectively, each modulated in accordance with the same signal. This occurs when both oscillators are operating and the keys K and K' are both closed.

It will be seen that the frequencies of the oscillation generators are wholly independent 85 of any variations which occur in the antenna 58, because no material reaction from the anode circuit to the grid circuit of the amplifier 50 can occur. Furthermore variations in impedance of the device 53 does not vary 90 the frequency of the wave generated by the oscillator O or the oscillators O and O' when both are operating, because no appreciable energy transfer from the anode circuit to the grid circuit of the device 50 occurs. When 95 the oscillators are once adjusted the transmitted frequency or frequencies remain constant.

The present application comprises continuing subject matter from applicant's Patents No. 1,537,941, issued May 19, 1925, and 100 No. 1,465,358, issued August 21, 1923.

It will be apparent that some features of the invention are peculiarly adapted for use in radio systems while other features are capable of a wider range of application and may be used in systems employing conductive lines either for signaling or for operation of mechanism from a distant point. The novel features believed to be inherent in the invention are defined in the appended claims.

What is claimed is:

1. A system comprising a thermionic repeater having an input circuit and a plate circuit, a source of waves or impulses other than said repeater connected to said input circuit to be repeated, a modulating device, a source of current common to and with respect to which said modulating device and said repeater are in parallel, and means for applying lower frequency waves or impulses 115 to said modulating device.

2. A system comprising an electron discharge repeater, a source of waves other than said repeater connected to the input circuit thereof to be repeated, a second electron discharge repeater and means for varying the space impedance thereof at a relatively low frequency rate, a source of space current common to said repeaters and with respect to which they are in parallel, said source of 120

space current being located in a path of high impedance to currents varying at the rate of said low frequency waves or impulses.

3. A system comprising an electron discharge repeater, input and output circuits therefor, a source of waves other than said repeater connected to one of said circuits, a modulating device, a source of constant current for supplying said repeater and modulating device in parallel, means for varying the impedance of said modulating device at a relatively low frequency rate, and means for preventing the waves or impulses from said source of waves from passing through said modulating device.

4. The method of modulating by means of a thermionic repeater and an impedance device which comprises producing uniform high frequency oscillations, supplying said uniform oscillations to the input circuit of the thermionic repeater, varying the repeating power of said repeater in accordance with the variations of potential across the impedance device, and preventing the flow 25 of any appreciable high frequency current through the impedance device.

5. A modulating system comprising means for producing carrier oscillations or impulses of one frequency varying in amplitude at a lower frequency, and means reproducing the complete amplitude variations for producing therefrom carrier oscillations varying in amplitude at the same low frequency rate but having a different relation between the maximum and minimum amplitudes.

40 6. A modulating system comprising means for producing carrier oscillations or impulses of one frequency varying in amplitude in accordance with a signaling wave, and means for producing therefrom carrier oscillations varying in amplitude in accordance with the same signaling wave but having a higher ratio between the maximum and minimum amplitudes.

45 7. The method of modulating which comprises successively varying the amplitude of a wave train of the same frequency in accordance with the same waves or impulses of a lower frequency.

50 8. The method of repeating by means of a repeater having input and plate circuits which comprises supplying a wave of non-uniform amplitude to the input circuit of the repeater, and varying the potential impressed upon the plate circuit of the repeater in accordance with the variations in amplitude of the non-uniform wave.

9. A system comprising an amplifying device, a second amplifying device having its input circuit connected to the output circuit thereof, and means for varying the amplifying power of said devices in accordance with the same series of electrical variations.

10. A system which comprises means for varying the amplitude of a high frequency

wave in accordance with a signaling wave, means for varying the electro-motive force supplied to the plate circuit of a repeater in accordance with the same signaling wave, means for applying a varied high frequency wave to the input circuit of the repeater, and means for causing varying leakage current in the repeater to compensate for the variations in the electro-motive force applied to the plate circuit. 75

11. The method of repeating by means of a repeater having a grid circuit and a plate circuit which comprises impressing an electromotive force on the plate circuit of a repeater to cause distortion of the repeated wave and impressing an electromotive force on the grid circuit in a manner tending to compensate for the distortion. 80

12. A system comprising a source of signaling waves or impulses, a variable impedance device, means for applying said waves to said device to vary the impedance thereof, a generator associated with said device whose oscillations are caused to vary in accordance with the impedance of said device, a repeater associated with said device whose repeating efficiency tends to vary in accordance with the impedance of said device, means for applying to said repeater waves produced by said generator, and means responsive to the action of said waves upon said repeater for compensating for the variations in the repeating efficiency thereof caused by said variable impedance device. 85 90 95 99

13. In combination, a carrier wave source, 100
a source of lower frequency waves, means
for modulating said carrier wave in accord-
ance with said lower frequency waves, a re-
peater for repeating the resultant modulated
wave, means for reducing the energy con- 105
sumption of said repeater when the ampli-
tude of said modulated wave is reduced, and
means acting synchronously with the varia-
tions in said modulated waves tending to
maintain the amplifying power of said re- 110
peater constant.

14. In combination, a highly inductive source of electromotive force, a variable impedance device and a plurality of discharge devices arranged in parallel with respect to 115 said source, means for supplying waves of carrier frequency to the input circuit of one of said devices, and means for feeding waves of said frequency from one of said devices to another thereof 120

15. A highly inductive source of electro-motive force, a variable impedance discharge device, means for varying the impedance of said device in accordance with sound waves, a plurality of discharge devices arranged in parallel to said discharge device with respect to said source, means for supplying waves of carrier frequency to the input circuit of one of said discharge devices, means for feeding waves of said fre- 130

- quency from said one device to another of said devices, and a grid leak path associated with one of said plurality of devices adjusted to increase the negative charge on the grid thereof in synchronism with increases of plate potential applied to the plate circuit thereof.
16. The method of repeating which comprises supplying waves to be repeated to the grid circuit of a repeater, causing variations of a lower frequency than said waves in the potential applied to the plate circuit of said repeater, and varying the charge on the grid of said repeater in synchronism with the lower frequency variations.
17. The combination of a variable impedance discharge device system and an oscillation generating discharge device system with an amplifying discharge device system, and means tending to maintain constant the sum of the currents through said systems.
18. The method of repeating waves which at times have a larger amplitude than at other times which comprises superimposing the waves on a unidirectional current and conserving the energy of the source of the unidirectional current by causing the average value of the unidirectional current to vary with the amplitude of the waves to be repeated in such a manner that as one increases the other increases and as one decreases the other decreases.
19. A transmitting system comprising a space discharge device having appropriate circuits and power sources connected thereto whereby its functions as a generator of carrier frequency waves, an amplifier in which the energy generated by said generator is amplified, a transmitting conductor system supplied by said amplifier, said amplifier having a space current circuit, and a signal-controlled variable impedance device connected in shunt to a portion of said circuit.
20. A transmitting system comprising a space discharge device having appropriate circuits and power sources connected thereto whereby it functions as a generator of carrier frequency waves, an amplifier controlled by said waves for producing waves of the same frequency and increased power, a radiating antenna system supplied with waves of increased power by said amplifier, said amplifier having an anode-cathode circuit, a variable impedance device connected in shunt to a portion of said circuit, and a speech frequency circuit for controlling the impedance of the variable impedance device.
21. A radio system comprising an amplifier, an anode-cathode circuit therein, a variable impedance device associated with said amplifier, a common source of current for said device and said amplifier, means for maintaining constant the sum of the current supplied from said source to said device and amplifier, and a source of high frequency waves connected to the input circuit of said amplifier.
22. A radio transmitting system comprising a frequency-setting oscillation generator of low power, an amplifying device for increasing the power of the waves produced, signal-controlled variable impedance means in shunt to the output circuit of said amplifier, means tending to maintain constant the sum of the currents supplied to said amplifier and variable impedance means, and a radiating antenna upon which the waves from the output circuit of said amplifier are impressed.
23. A thermionic system comprising a discharge device and appropriate circuits whereby said device functions as a generator of oscillations, a second device adapted to function as a repeater to repeat the generated oscillations, filaments in said devices, an alternating current heating source for the filaments of said devices, and means whereby the disturbing effect produced by said source upon one of said devices is compensated for by the effect produced upon the other of said devices.
24. A system for multiplexing a radio telephone system comprising an antenna tuned to a certain transmitting wave length, an additional capacity connected in parallel to the aerial-ground capacity of said antenna for tuning said antenna to another longer wave length, and a loop circuit in series with said additional capacity tuned to offer a very high impedance to currents corresponding to said first mentioned wave length.
25. A transmission system comprising means for impressing on an antenna signaling waves of different frequencies, tuning elements for tuning said antenna to one of said frequencies, additional tuning elements arranged in shunt branches to tune said antenna to each of said other frequencies respectively, and impedance means in series with each additional tuning element to prevent the passage therethrough of the waves of an adjacent frequency.
26. A signaling system comprising an antenna tuned to a given frequency, means for impressing currents of said frequency and a series of other frequencies upon said antenna, a series of branch circuits each of which comprises tuning means for tuning said antenna to one other said series of frequencies, and an impedance means offering high impedance to one other of said series of frequencies, the first of said branch circuits being in shunt to the radiating capacity of said antenna and the remaining branch circuits being arranged in shunt to the tuning means of the preceding branch circuit respectively.
27. An antenna system comprising an antenna circuit, means for impressing thereon two signaling waves, means for tuning said

- antenna to the one of said waves having the lower frequency, a shunt circuit for tuning said antenna circuit to said wave of higher frequency, and means in said shunt circuit 5 offering a high impedance to said waves of lower frequency, whereby the radiating efficiency of said antenna system for said waves tends to be equalized.
28. An antenna circuit, means for conveying waves to said antenna to be transmitted including a discharge device having its output circuit coupled to said antenna, said output circuit being tuned to resonance to the waves to be transmitted, and paths in shunt 10 to said output circuit corresponding to other waves to be impressed upon said antenna, each being tuned to offer low impedance to one of said other waves.
29. A multiplex transmission system comprising a signaling circuit, a plurality of circuits for impressing signaling waves of different frequencies thereon, each of said circuits including a path of low impedance for waves of the frequency to be impressed upon the 15 signaling circuit by said one circuit and also including means in shunt to said path of high impedance for waves of that frequency but of low impedance to waves of the frequencies impressed by another of said circuits.
30. An antenna circuit and a plurality of transmission circuits coupled thereto, each transmission circuit including a path of low impedance to waves of the frequency or frequencies that are to be transmitted by said 20 circuit, and paths in shunt to said first mentioned path of low impedance to the waves to be transmitted by each of said other transmission circuits.
31. A system for modulating by means of a vacuum tube having a grid circuit and a plate circuit which comprises means for impressing an electromotive force of modulating frequency on the plate circuit and means for changing the potential of the grid of said 25 device in opposite phase relation with respect to said force of modulating frequency.
32. A vacuum tube amplifying system for radio frequency currents comprising at least two tubes in tandem, and means for coupling the plate-filament circuit of one of said tubes to the grid-filament circuit of the next succeeding tube comprising an impedance element in the plate-filament circuit of the first tube through which high frequency currents 30 are caused to flow to set up high frequency voltages across the grid-filament circuit of the second tube, a choke coil of sufficient impedance at frequencies to be amplified for preventing high frequency variations from 35 passing therethrough located in series with the space current path of said first tube, and a condenser having one terminal connected to the common point of said choke coil and the plate of said first tube and the other terminal to a point on said impedance element 40 remote from the filament of said first tube.
33. In a wave signaling system, means for generating continuous high frequency carrier oscillations, an amplifier for amplifying said carrier oscillations, a source of uni-directional voltage for said amplifier, a variable impedance in series in a direct current circuit with said source of voltage, means for keeping the current from said source substantially constant, and means for varying said impedance in accordance with signals. 45
34. In a wave signaling system, a generator of high frequency oscillations having an output circuit, a vacuum tube amplifier for amplifying said high frequency oscillations, said amplifier having an input circuit and an output circuit, said input circuit being associated with the said output circuit of said generator, a source of current in the output circuit of said amplifier, a variable resistance in shunt to said source of current, and means for varying said resistance in accordance with signals. 50
35. In a wave signaling system, a generator of continuous high frequency oscillations of constant amplitude, an output circuit for said generator, a vacuum tube amplifier having input electrodes and output electrodes, an input circuit for said amplifier, said input circuit being associated with the output circuit of said generator, an output circuit for said amplifier including said output electrodes, a load circuit associated with said output circuit, a source of uni-directional current included in the output circuit of said amplifier, an inductance coil in series with said source of current and included in said output circuit said coil being operable to maintain the flow of current from said source substantially constant, a second vacuum tube 55 comprising a plate, a grid and a filament, said plate and filament being connected in series with said source of current and said inductance coil and in shunt to the output electrodes of said amplifier, an input circuit for said second vacuum tube and a microphone associated with said last mentioned input circuit and operable to vary the impedance between the plate and filament of said second vacuum tube in accordance with signals to be transmitted, the arrangement being such that continuous high frequency oscillations from said generator are amplified by said amplifier and simultaneously 60 modulated by diversion of current from said amplifier in accordance with signals impressed on said microphone and furthermore that the frequency of said oscillations is substantially unaffected by variations in the constants of said load circuit. 65
36. The method of producing signal modulated high frequency carrier current of substantially uniform frequency which consists in generating unmodulated high frequency carrier current of substantially con- 70 75 80 85 90 95 100 105 110 115 120 125 130

stant frequency, impressing said unmodulated carrier current upon the input circuit of an amplifier, supplying current of substantially constant value to the output circuit of said amplifier and variably diverting said current away from said amplifier in accordance with signals to be transmitted.

37: In a wave signaling system, means for generating continuous high frequency carrier oscillations, an amplifier for amplifying said carrier oscillations, said means for generating comprising a vacuum tube system generator producing continuous high frequency oscillations of substantially constant amplitude and frequency whereby such oscillations are supplied unmodulated to the modulating amplifier, a source of uni-directional voltage for said amplifier, a variable impedance in series in a direct current circuit with said source of voltage, means for keeping the current from said source substantially constant, and means for varying said impedance in accordance with signals.

38: In a wave signaling system, a generator of high frequency oscillations having an output circuit, a vacuum tube amplifier for amplifying said high frequency oscillations, said amplifier having an input circuit and an output circuit, said input circuit being associated with the said output circuit of said generator, a source of current in the output circuit of said amplifier, a variable resistance in shunt to said source of current, and means for varying said resistance in accordance with signals, said generator comprising a vacuum tube system generator producing continuous high frequency oscillations of substantially constant amplitude and frequency, whereby such oscillations are supplied unmodulated to the modulating amplifier.

39: In a wave signaling system, a generator of continuous high frequency oscillations of constant amplitude, an output circuit for said generator, a vacuum tube amplifier having input electrodes and output electrodes, an input circuit for said amplifier, said input circuit being associated with the output circuit of said generator, an output circuit for said amplifier including said output electrodes, a load circuit associated with said output circuit, a source of uni-directional current included in the output circuit of said amplifier, an inductance coil in series with said source of current and included in said output circuit said coil being operable to maintain the flow of current from said source substantially constant, a second vacuum tube comprising a plate, a grid and a filament, said plate and filament being connected in series with said source of current and said inductance coil and in shunt to the output electrodes of said amplifier, an input circuit for said second vacuum tube and a microphone associated with said last mentioned

input circuit and operable to vary the impedance between the plate and filament of said second vacuum tube in accordance with signals to be transmitted, the arrangement being such that continuous high frequency oscillations from said generator are amplified by said amplifier and simultaneously modulated by diversion of current from said amplifier in accordance with signals impressed on said microphone and furthermore that the frequency of said oscillations is substantially unaffected by variations in the constants of said load circuit, said generator comprising a vacuum tube system generator producing continuous high frequency oscillations of substantially constant amplitude and frequency, whereby such oscillations are supplied unmodulated to the modulating amplifier.

40: The method of producing signal modulated high frequency carrier current of substantially uniform frequency which consists in generating unmodulated high frequency carrier current of substantially constant frequency by employing a vacuum tube system generator producing continuous high frequency oscillations of substantially constant amplitude and frequency, impressing said unmodulated carrier current upon the input circuit of an amplifier, supplying current of substantially constant value to the output circuit of said amplifier, and variably diverting said current away from said amplifier in accordance with signals to be transmitted.

41: The method of varying the amplification of a vacuum tube amplifier which consists in adjusting the static grid potential in accordance with the amplitude of the envelope of the alternating input energy applied to the tube.

42: The method of operating a translating circuit, including a three-element vacuum tube, which consists in so controlling the static grid potential of the vacuum tube in accordance with the amplitude of the envelope of the alternating input energy that a predetermined relation between the input energy applied to the system and the output energy from the system will be obtained.

43: The method of operating a translating circuit, including a three-element vacuum tube, which consists in so controlling the static potential of the grid of the tube in accordance with the amplitude of the envelope of the alternating input energy that the output energy will be a maximum for a predetermined amplitude of the input energy.

44: The method of operating a translating circuit, including a three-element vacuum tube, which consists in so controlling the static potential of the grid of the tube in accordance with the amplitude of the input energy that the system will discriminate

against input energies having amplitudes less than a predetermined maximum.

45. The method of operating a translating circuit, including a three-element vacuum tube, which consists in so controlling the static potential of the grid of the tube in accordance with the amplitude of the envelope of the alternating input energy that the system will discriminate against input energies having amplitudes greater than a predetermined amplitude.

46. The method of operating a vacuum tube amplifier which consists in shifting the operating point of the tube along its characteristic axis in accordance with the amplitude of the envelope of the alternating input energy.

47. In a translating system, a three-element vacuum tube, means to apply energy variations to said tube and means to adjust the working point of said tube along its characteristic axis in accordance with the amplitude of the envelope of the alternating energy variations.

48. In a wave signaling system, a generator of high frequency oscillations having an output circuit, a vacuum tube amplifier for amplifying said high frequency oscillations, said amplifier having an input circuit and an output circuit, said input circuit including a leak resistance shunted by a condenser and being associated with the said output circuit of the said generator, a source of current in the output circuit of said amplifier, a variable resistance in shunt to said source of current, and means for varying said resistance in accordance with signals.

In witness whereof, I hereunto subscribe my name this 29th day of December, A. D. 1921.

RAYMOND A. HEISING.
